[57] CLAIM

The ornamental design for a cushion unit for lifting a handicapped person, as shown and described.

DESCRIPTION

FIG. 1 is a front, top and right side perspective view of a cushion unit for lifting a handicapped person showing my our design;

FIG. 2 is a front elevational view thereof;

FIG. 3 is a rear elevational view thereof;

FIG. 4 is a right side elevational view thereof, the left side being a mirror image of that shown;

FIG. 5 is a top plan view thereof; and,

FIG. 6 is a bottom plan view thereof.

FIG. 3.

FIG. 2.

FIG. 6.
